William P. Yant, Pittsburgh, Pa., assignor to
Mine Safety Appliances Company, Pittsburgh,
Pa.

Application April 18, 1939, Serial No. 84,372

Term of patent 14 years

To all whom it may concern:

Be it known that I, William P. Yant, a citizen of the United States, residing at Pittsburgh, in the county of Allegheny and State of Pennsylvania, have invented a new, original, and ornamental Design for Explosives Carriers, of which the following is a specification, reference being had to the accompanying drawing, forming a part thereof.

Fig. 1 is a front perspective view of an explosive carrier showing my new design; and
Fig. 2 is a top plan view thereof.

I claim:

The ornamental design for an explosives carrier, as shown.

WILLIAM P. YANT.
